CLAIM

The ornamental design for a syringe hand grip adapter as shown and described.

DESCRIPTION

FIG. 1 is a front perspective view of the syringe hand grip adapter of the present invention;

FIG. 2 is a rear perspective view;

FIG. 3 is rear plane view thereof;

FIG. 4 is a front plane view thereof;

FIG. 5 is a right side view thereof;

FIG. 6 is a left side view thereof;

FIG. 7 is a bottom plane view thereof;

FIG. 8 is a top plane view thereof; and,

FIG. 9 is a perspective view thereof, showing the syringe hand grip adapter in a state of use in its environment, with a syringe barrel and plunger.

(Continued)

The broken lines, showing a syringe barrel and plunger, are for the purpose of depicting environmental structure, and form no part of the claimed design.
